DOOR AND STEP MECHANISM

Dwight E. Austin, Pontiac, Mich., assignor to
 Yellow Truck & Coach Manufacturing Company, Pontiac, Mich., a corporation of Maine

Application October 11, 1940, Serial No. 360,750

6 Claims. (Cl. 280—166)

This invention has for its object the provision of an improved passenger bus construction to facilitate the movement of passengers into and out of the coach body. It relates more particularly to the control and operating mechanism for the closure door and retractible step structure and among other things enables the operator to open the door by itself or simultaneously to project an auxiliary step for the accommodation and safety of passengers boarding or leaving the conveyance.

In the preferred embodiment disclosed, the usual door for the opening in the curb side wall opposite the driver's station closes against a fixed step at the loading platform leading into the passenger space and a secondary step is housed out of the way under the step well to be projected downwardly and outwardly to a convenient height ahead of the door opening. Use of the secondary step under control of the operator will be unnecessary when the door is opened beside a high city street curb or beside an elevated landing at a regular stop station but in the absence of raised landing ground the projection of the retractible step will serve to decrease step height distance from the ground. For simplification of structure the step operating mechanism is arranged to be clutched at will with the door operating mechanism and a single control handle serves as an agency through which the door is opened and closed either alone or selectively in unison with the projection and retraction of the secondary step.

For a more detailed explanation reference will be made to the accompanying drawings in which Figure 1 is a transverse section of a motor coach at the driver's station; Figure 2 is an enlarged sectional view with parts broken away, showing the door and step structure and may be considered as taken on line 2—2 of Figure 3; Figure 3 is a horizontal sectional view of the door and step operating mechanism as viewed on line 3—3 of Figure 2; Figure 4 is a detail view on line 4—4 of Figure 2; Figure 5 shows the operating handle in section together with a portion at the upper end of a control column assembly; Figure 6 shows the lower end of the control column assembly in section as on line 6—6 of Figure 7 and Figure 7 is a transverse section taken on line 7—7 of Figure 6.

In the several figures all of the parts are shown in the relation they assume with the door open and the auxiliary step retracted.

As usual the operator is stationed in the front of the vehicle immediately behind the windshield

and opposite the curb side as indicated by the position of the steering wheel 1 in Figure 1. A loading platform 2 beside the operator leads to the passenger seating space with a step well providing a fixed step 3 immediately adjacent the side wall opening at the curb. This opening at the front of the vehicle serves for either or both the loading and unloading of passengers and is closed by the conventional door structure 4 hinged to the coach along its forward edge.

The inner panel of the door contains a slot 5 leading to a guide track for a pair of rollers 6 carried on the end of a swinging door operating lever or bell crank 7 which is so arranged as to 15 provide a grab rail for the assistance of passengers moving through the door opening. The door operating lever 7 projects through an opening in a cover or trim panel 9 and is pivotally mounted at an intermediate point on a vertical pin carried by the mounting bracket 10. Its inner arm is joined by a pivot pin 11 to an adjustable clevis on the outer end of a transverse connecting rod 12 concealed behind the appearance panel 9 and provided at its inner end with a connecting head 13 having forwardly extending ears secured by a pin 14 to a rock lever 15 forming a part of a vertical control column assembly which also includes a series of concentric nested tubes 16, 17 and 18.

30 The outermost column tube 16 is a fixed or stationary housing and spacer mounted at its lower end in a supporting bracket 19 and provided with needle roller bearing assemblies 20 at its upper and lower ends in which the intermediate tube or hollow shaft 17 is rockably mounted. At its lower end the rockshaft 17 is welded or otherwise secured to the rock lever 15 and at its upper end has fixedly secured thereto the split contractible end of a laterally projecting lever 21 as best seen in Figure 5. The free end of the lever 21 has a split contractible eye supporting a pivot pin 22 on an axis transverse of and radially spaced from the axis of the rockshaft 17 and on which is pivotally secured the lever or handle 23. 35 Secured to the handle 23 by a fastening bolt 24 is an antifriction bearing assembly 25 for a freely rotatable knob or handball 26 within easy reach of the operator adjacent the steering wheel 1.

50 When the open door 4 is to be closed the operator grasps the knob 26 and swings the lever 23 away from him or toward the right which movement is transmitted through the vertical control shaft 17 to the rock lever 15 at the bottom of the control assembly and through the

transverse connecting rod 12 to the bell crank 1 and thereby swings the door 4 into closed position against the fixed step 3. The door is actuated to open position through the motion transmitting linkage referred to, when the handle 23 is swung back toward the driver. In either limit of travel an over center relation is established to hold the door against accidental displacement by pressure applied directly thereto. The over center relation will be best appreciated from an inspection of Figure 3 where it will be noted that a line drawn through the pivot pins 14 and 11 will extend forward of the axis of the rockshaft 17. To define the opposite limits of movement of the rock lever 15, its opposite sides are provided with abutment faces 27-27 for engagement with stops 28-28 carried by the stationary bracket 19.

Normally pocketed beneath the step 3 is the secondary step structure 29 which in general includes a tread plate on a U-shaped or box member whose side walls terminate on a diagonal line with outturned flanges which rest upon and are secured by welding or the like to a pair of channelled rails or track bars 30 and 31 extending diagonally upwardly on opposite sides of the step well. Each of the channel sectioned rails opens outwardly and is mounted for relative sliding movement outwardly and downwardly on a pair of spaced rollers 32, fastened as seen in Figure 4, on a trunnion stud 33 to the coach structure. The outward and downward sliding movement referred to, projects the step to the dotted line position as seen in Figure 2 just ahead of the door opening and immediately below the fixed step 3.

Operation of the step concurrently with door operation is effected through suitable linkage including a rockshaft 34 located beneath the loading platform 2 by a pair of bearing brackets 35. At its rearward end and in line with the guiding and supporting rail 30, the rockshaft 34 carries a lever arm 37 whose free end is connected by a link 38 with a bracket 39 on the inner end of the guide rail 30. Similarly the companion guide rail 31 has its end bracket 40 joined by a link 41 with another lever 42 keyed on the rockshaft 34 so that as the rock levers 37 and 42 are swung with the shaft, their movement is transmitted through the links 38 and 41 to project or retract the step structure. At its forward end and beyond the trim panel 9, the rockshaft 34 is fixed to a lever 43 whose free end is joined by the link 44 to the lower arm of a vertical rock lever 45 mounted on a suitable trunnion 46. The upper arm of the lever 45 is connected by a jointed coupling member 47 with the outer end of a connecting rod 48 located immediately below the door operating rod 12 and provided at its inner end with a coupling head 49 secured by a pivot pin 50 to a rock lever 51 at the base of the control assembly. A headed fastening stud 52 secures the lever 51 to the stationary bracket 19 and provides the fulcrum therefor, there being a needle roller assembly 53 between the parts to reduce friction.

In the space between the rock levers 51 and 15 is an axially shiftable member 54 welded or otherwise secured to the innermost tube or shift rod 18 whose lower end is piloted in the upper end of the fastening stud 52. This axially shiftable member 54 has fixedly secured thereto a pair of spaced axially extending clutching pins 55 each of which is slidably received within the rock lever 51 with at least one of the pins having its lower

end projectible into locking relation with an aligned recess in the fixed bracket 19, whereby to hold the step operating lever 51 against rotation. Each pin also has its upper end projected above the member 54 so that it can be shifted into locking engagement with a receiving recess drilled into the under face of the rock lever 15. By reason of the relation of parts illustrated, the clutching pins 55 upon being lifted by the member 54 will move out of locking engagement with the stationary bracket 19 and into locking engagement with the lever 15 for keying the step operating lever with the door operating lever. The axial shifting of the parts is transmitted by the rod 18 from the hand lever 23 under control of the operator through the interconnection shown in Figure 3 wherein the lever 23 is provided with a transverse pin 56 fitted to a slot in the head of a stud 57 swivelly secured, as by means of screw threads, in the upper end of the shift rod 18.

In the retracted position of the step the weight of the column parts maintains the clutch pins 55 in locking relation to the bracket 19 and the coupling of the step and door operating mechanisms is effected when the operator lifts the clutching parts by depressing the hand knob 26 to move the hand lever 23 about its pivot pin 22 as indicated by the broken line in Figure 5. If the hand lever is both depressed and swung through its door opening path the step will be projected in unison with the movement of the door so that at the will of the operator the mechanism can be actuated either to open the door by itself or simultaneously to open the door and project the step to take care of the various situations encountered in the normal travel of a road vehicle with reference to landing height and ground levels.

40 I claim:

1. In combination, door and step operating mechanisms, a manually operated rockshaft fixedly connected with the door operating mechanism, a manually controlled clutch device having two positions of setting and being engageable with the step operating mechanism in both positions, an anchoring member engageable by said clutch device upon shifting the clutch device selectively to one of said positions and clutch engaging means connected with the rockshaft and engageable by said clutch device upon shifting the clutch device selectively to the other of said positions.

2. A control assembly for door and step operating mechanisms including a pair of concentric nested shafts, one of which is rockable and has fixed connection to one of said mechanisms, a hand lever for rocking said shaft, means pivotally mounting the hand lever on the rockshaft on an axis transversely related to and radially spaced from the axis of the rockshaft, means for transmitting movement of the lever about said transverse axis to shift the other shaft axially and a clutch controlled by said axially shiftable shaft to couple the rockshaft with the other of said mechanisms.

3. In combination with a closure door and a retractile step, of a rockshaft having an operating handle at one end, a rocking member mounted at the opposite end of the rockshaft and connected with the door, a second rocking member connected with the step, a supporting bracket pivotally mounting the step rocking member in neighboring relation with the door rocking member and in coaxial relation with the rockshaft

and a clutch key slidably engaged with the step rocking member and shiftable in opposite directions to engage at one end with the door rocking member when shifted in one direction and to engage at its opposite end with the supporting bracket when shifted in the other direction.

4. A control assembly for door and step operating mechanisms, including a rockshaft arranged for operative connection with one of said mechanisms, a lever mounting member rigid with the shaft, a hand lever pivotally connected with said lever mounting member on a transversely extending axis spaced radially of the shaft axis, a second shaft connected with said lever for relative axial shifting movement and a clutch controlled by the shifting of the second shaft for operatively coupling the first shaft with the other of said mechanisms.

5. A control assembly for door and step operating mechanisms, including a stationary bracket, a pair of rock levers pivotally mounted in tandem by said bracket on a common axis and connected to said mechanisms, respectively, a clutch pin

10 axially slidable in one of said levers with opposite ends projectible in alternate relation into and out of locking recesses in the stationary bracket to lock the lever against movement and in the other lever to lock the levers together for movement in unison.

15 5 6. A control assembly for door and step operating mechanisms, including a rockshaft having a rock lever fixed at its lower end for connection with one of said mechanisms, a stationary bracket providing a locating bearing for the shaft, a second lever mounted in the bracket and connected with the other of said mechanisms, an axially shiftable member keyed to the last mentioned lever with a projecting portion for clutch connection with the first mentioned lever, an operating rod for the member arranged in concentric nested relation with said rockshaft and an actuating handle operatively connected to both the shaft and the rod and arranged to control the axial adjustment of the rod and the rocking movement of the shaft.
